UNITED STATES PATENT OFFICE.

HERBERT H. MACOMBER, OF KENDALLVILLE, INDIANA, ASSIGNOR TO FLINT & WALLING MANUFACTURING COMPANY, OF KENDALLVILLE, INDIANA, A CORPORATION OF INDIANA.

WINDMOTOR.

1,148,519.

Specification of Letters Patent. Patented Aug. 3, 1915.

Application filed April 23, 1913. Serial No. 762,998.

To all whom it may concern:

Be it known that I, HERBERT H. MACOMBER, a citizen of the United States, residing at Kendallville, Noble county, Indiana, have 5 invented a new and useful Windmotor, of which the following is a specification.

This invention relates to wind motors or windmills.

This invention has utility when embodied 10 in features of construction and control of windmills, especially of the vertical or solid wheel type.

Referring to the drawings: Figure 1 is a fragmentary side elevation of an embodiment of the invention in a solid wheel type of windmill; Fig. 2 is a section of the governor spring on the line II—II, Fig. 1, looking in the direction of the arrow; Fig. 3 is a perspective view of the one-piece frame; 15 Fig. 4 is a fragmentary section of the stem mounting in the one-piece frame; Fig. 5 is a fragmentary elevation from the opposite side to the showing in Fig. 1, in each instance the vane being in position to hold the wheel into the wind or in running position; Fig. 6 is a fragmentary plan view of the mill of Fig. 1; Fig. 7 is an elevation of the mill from the back, or side opposite the windwheel, and with the vane in position to 20 hold the windwheel out of the wind; Fig. 8 is a vertical section of the yoke on the line VIII—VIII, Fig. 5; Fig. 9 is a bottom plan of the yoke on the line IX—IX, Fig. 8, looking in the direction of the arrow; and Fig. 10 is a section on the line X—X, Fig. 7, looking in the direction of the arrow.

The windmill tower or mounting 1 has the swivel bearing or turntable 2 through which may extend the stem 3 (Figs. 1, 4) carrying 40 the main integral or one-piece frame having on its lower side the swivel bearing 4 coacting with the bearing 2. The upper end of the stem 3 is tapered upwardly to snugly coact with the frame seats 6, 7, and is rigidly 45 locked in such assembled position by swaging 8 of the upper extremity of the stem 3 into securing relation, thereby maintaining the frame 9 and its stem 3 together as a unit.

The windwheel comprises the central 50 bearing or overhanging mounting cone 10 having the concentric blade mountings 11, 12. Clips 13 on the inner circular mounting 11 engage the blades 14 to positively hold their inner ends, while the embracing members 15 slipped outwardly into snugly fit-

ting locking relation as to the curved or dished blades 14 fix the angle of pitch of the blades as to the outer circular mounting 12 passing through the blades. The circular 55 mountings 11, 12, are held in position by the radiating arms 16, 17, carried by the cone hub 10. The wheel as described, when built up of metal, may have its resistance to weather deterioration by a coating, as galvanizing. The outer portions of the 60 blades, where the strains are greatest, are securely held by the plate members 15, resisting in their strongest direction, thereby producing maximum of strength in a light structure and by a device having no connection liable to weather weakening.

The windwheel is fast to the windwheel 65 shaft 18 having secured thereto the pinions 19, 20, intermediate the bearings 21, 22, for the shaft 18 in the frame 9. While the 70 windwheel is overhung, this transmission means from the windwheel shaft is a balancing thereof and a stiff construction in itself. Furthermore, it is to be noted the bearing 75 21 is long and within the load plane of the blades. The pinion 19 is in mesh with the crank or gear wheel 23 held by the set screw 24, entering the groove 25 for rotative mounting on the crank wheel shaft 26, overhung from each end of the bearing 27 in 80 the main frame 9. In mesh with the pinion 20 is the second crank or gear wheel 28 held by key 29 to rotate with the crank shaft 26. With the crank 23 loose and the crank 28 fast, differences in alinement or 85 wear, or from any other cause, may be taken up in the transmission and each crank 90 carry its portion of the work (Figs. 5, 6).

Each crank wheel 23, 28, carries a wristpin 30 which may be radially adjusted as 95 desired in the corresponding openings 31, (Fig. 7) so that each of the pitmen 32 in their straight upward extension may engage the common pivot pin 33, locked by the set screw 34 medially of the length of the pin 33. This screw 34 is carried by the walking beam 35 mounted by the pivot pin 36 in the walking beam bracket 37 forming an upwardly extending portion of the main 100 frame 9, distributing such work along the windwheel shaft 18 in such a manner as to effectively neutralize the windstrain tugs and pulls transmitted from the windwheel in the wind shiftings and irregular workings due to atmospheric conditions. While 105 110

the spaced bearings 21, 22, and their relatively long extent are material features in contributing to the life of the structure, the two gears with connecting rods, walking beam and yoke driven thereby, for taking the drive from the shaft 18 are great factors in the efficiency of the mill in giving the mill steadiness of operation under the most trying conditions.

10 On the pin 33 and disposed outside the walking beam 35 and between the pitmen 32 is the Y-yoke 38 forming a reciprocable member driven by the pitmen and guided by the walking beam. The upper arms of the 15 Y are pivotally connected to the pin 33, while the lower stem has a seat 39 with lugs 40 rising therefrom just above the openings 41 therethrough so that the U-bolt fastening means may firmly lock the angle 20 pump rod 43 over the lugs 40 and against the seat 39. Accordingly in the lift movements of the Y-yoke 38, the load is taken by the lugs 40, thereby removing shearing action from the U-bolt 42. As the pair of 25 openings in the pump rod 43 are properly spaced to receive the lugs 40 and afford registry with the two openings in the yoke stem, the insertion of the U-bolt and locking it in position provides a tight connection 30 firm against any working loose (Figs. 5, 8, 9).

In the main frame 9 adjacent the bearing 27 is the opening 44 (Fig. 3) with which 35 engages the pin 45 for the upper hinge bracket 46 of the vane 47. In the main frame 9 and in line with the opening 44 and therebelow is the bracket 48 rigid with the main frame 9 (Figs. 1, 3). This bracket 48 affords a 40 seat for the lower end of the pivot pin 45 through the opening 44. On this pin 45 adjacent the bracket 48 is the lower hinge bracket 49 for the vane 47.

With the windwheel in gear, or for running, the vane is disposed at right angles 45 thereto and slightly to one side of the wheel center (Fig. 6). The vane is yieldably held in this running position by the governor. Mounted on the pin 45 just above the lower hinge bracket 48 is the outwardly extending 50 arm 50 to the end of which is hooked the adjustable link 51 connected to the U-rod 52 having at its end remote from the frame 9 the hooks 53 extending over to engage a coil of the compression governor spring 54. The 55 opposite end of the spring 54 is engaged by the hooks 55 of U-rod 56 similar to the rod 52 but oppositely extending to be anchored by the link 57 to the vane 47 (Figs. 1, 2).

To limit the swing of the vane away from 60 the windwheel in throwing the windwheel into gear, there is the hook 58 on the frame 59 of the vane. The hook 60 engages this frame 59 as guided to position by the rod 61 sliding through the hook 58. The opposite 65 end of the rod 61 is mounted by the pin 62

on the arm 63 having the pivot pin 64 attaching it to the boss 65 on the main frame 9. This arm 63 is yieldably held in position at right angles to the line of the windwheel shaft 18 (Fig. 6). The arm 63 has lateral extensions 66, 67, each carrying a bolt 68 surrounded by a compression spring 69, so that the heads of the bolts are yieldably thrust against the stops 70 on the frame 9 to form cushions in sudden lunges to 75 which the arm may be subjected. Accordingly when the vane 47 swings the windwheel into gear, the cushion pocket 66 takes up the concussion thereby eliminating excessive strains from the vane, frame and entire windmill structure, a feature materially contributing to the elimination of breakage in the mill and lengthening the life of an easy running machine.

For pulling the vane 47 out of gear, the 85 flexible line or connection 71 is connected to the frame member 59 of the vane and extends about the pulley 72 (Figs. 1, 6) on the arm 63, and thence over the pulley 73 to guide the line through the pump rod 90 opening 74 in the main frame 9. A swinging of the vane violently by pulling the line 71, or by the wind automatically acting upon the spring governor to throw the windwheel out of the wind, is taken care of 95 to avoid concussion by the vane striking the stop 74 on the arm 63, and the arm yielding at its compression cushion 67.

In pulling the line 71 to bring the windwheel out of gear, the line 71 becomes taut 100 under the trigger 75 (Figs. 1, 7) to lift this trigger so that in the swinging out of gear of the vane 47, this trigger 75 strikes the end of the arm 76 pivoted on the rod 45. This arm 76 medially of its length has the 105 lug 77 connected to which is the rod 78 having the compression spring 79 holding this rod into yieldable connection with the bracket 80 of the brake shoe 81. This curved brake face 81 is mounted by the arms 110 82 to swing from the bearings 83 in the long bearing 21 of the main frame 9 (Figs. 3, 6). Accordingly when the governor controls the swinging of the windwheel out of the wind for slackening speed, this automatic 115 action does not stop the wheel necessarily, thereby checking the effective wind action upon the wheel and still permitting the desired service to be performed. This swinging out from governor action does not set 120 the brake. The brake as shown is set only by the pulling of the line 71 which through the trigger 75 causes the arm 76 to yieldably force the brake shoe 81 to engage the inner face 84 of the wheel cone 10.

To preclude a locking of the wheel by this 125 brake, the arm 76 has at its mounting end a lug 85 in the path of the lug 86 on the vane hinge bracket 46. When the vane 47 swings out of gear, the lug 86 moves away 130

from the lug 85 and thus in the automatic action or even in the manual throw off there is no driving connection between these lugs to effect the brake 81. However the setting 5 of the brake 81 in the manual throw out of the mill, moves the arm 76 and likewise the lug 85, so with the brake 81 thus set, any moving of the vane hinge bracket 46 causes its lug 86 to act upon the lug 85 to swing the 10 arm 76 back in following the trigger 75 away from the wheel and thus positively withdraw the brake 81 through the rod 78.

In the structure as shown, oil cups are disposed above the various bearings to provide proper lubrication. 15

What is claimed and it is desired to secure by Letters Patent is:

1. In a windmill, the combination with a blade provided with an opening there- 20 through, a first member extending through said opening, and a blade embracing member having an opening therethrough for the blade, said embracing member being anchored to the first member to fix the pitch 25 of the blade.

2. A windmill comprising concentric blade mountings, a series of blades through which the outer mounting extends, and means anchored to the outer mounting and embrac- 30 ing the blades to fix the pitch of the blades as to the mounting.

3. A windmill frame provided with a swivel bearing, said frame having an annular tapered seat extending upwardly from 35 the bearing, and a stem engaging said seat and having swaged connection against relative movement as to the frame to form a guide.

4. A windmill comprising a windwheel, a 40 brake therefor, a vane, means connected to the vane for moving the vane, and a device movable relatively to the vane and actuated by the means from the vane for setting the brake.

45 5. A windmill comprising a windwheel, a pivoted brake therefor, a vane, a governor against the resistance of which said vane may move and means actuated by said vane to control automatically the wheel independ- 50 ently of setting the brake.

6. A windmill comprising a windwheel, a pivoted brake therefor, a vane for the wind- 55 wheel, a governor connected to the vane for controlling the wheel, and connections be- 60 tween the brake and governor for releasing the brake as the governor moves the vane to throw the wheel into the wind.

7. A windmill comprising a windwheel, a 65 brake therefor, a vane, a trigger on the vane, a connection for pulling the vane against the wheel, and means actuated by the trigger for setting the brake.

8. A windmill comprising a windwheel, a 70 brake therefor, a vane, a trigger on the vane, a connection for pulling the vane against the 75

wheel, means actuated by the trigger for setting the brake, and additional means for releasing the brake upon reverse movement of the vane.

9. A windmill comprising a windwheel, a 70 brake therefor, an actuating arm yieldably connected to the brake, brake setting connections for moving the arm in one direction, and brake releasing connections for moving the arm in the opposite direction. 75

10. A windmill comprising a windwheel, a vane therefor, a frame on which the vane and wheel are mounted, and a yieldable arm movable independently of the frame and extending from the frame and in the path of 80 the vane to take the concussion of the vane as the vane moves theretoward in throwing the wheel out of the wind.

11. A windmill comprising a windwheel, a vane therefor, a frame on which the vane 85 and wheel are mounted, a pull out line for the vane, a buffer arm pivotally mounted on and movable independently of the frame, and a pulley for the line carried by the arm.

12. A windmill comprising a windwheel, 90 a vane therefor, a frame on which the vane and wheel are mounted, and a yieldable buffer arm movable independently of the frame and connected to cushion the limiting movements of the vane. 95

13. A windmill frame comprising a pair of windwheel shaft bearings, and a crank shaft bearing parallel with the windwheel shaft bearings and disposed between the windwheel shaft bearings. 100

14. A windmill frame comprising a bracket for carrying a walking beam bearing pin, a crank shaft bearing, and a pair of windwheel shaft bearings disposed one on each side of the plane of the bracket and 105 crank shaft bearing.

15. A windmill frame comprising a walking beam bearing, a swivel supporting bearing, and a pair of windwheel shaft bearings disposed one on each side of the plane of 110 the walking beam bearing and swivel bearing.

16. A windmill frame comprising a swivel windmill frame supporting bearing, a pair of windwheel shaft bearings one on each 115 side of the swivel bearing and alined laterally of said swivel bearing, and a crank shaft bearing in the plane with the swivel bearing and at right angles with the alined windwheel shaft bearings. 120

17. A windmill frame comprising a swivel bearing, and axially at right angles thereto and laterally thereof a first bearing, and second and third bearings, said second and third bearings being in alinement, parallel 125 to the first bearing and disposed beyond the ends of the first bearing.

18. A windmill frame comprising a sup- 130 porting bearing, and axially at right angles thereto and laterally thereof a first bearing,

- second and third bearings in alinement with each other and parallel to the first bearing on the opposite side of the supporting bearing from the first bearing.
- 5 19. A windmill frame comprising a supporting bearing, and axially at right angles thereto a first bearing, alined second and third bearings, and a fourth bearing on the side of the first bearing remote from the 10 second and third bearings.
20. A windmill frame comprising a central tubular portion, a pair of alined arms extending laterally from adjacent said tubular portion, and on one side of said frame a 15 portion rising adjacent the tubular portion from the opposite side thereof of the alined arms.
21. A three armed windmill frame having a central tubular portion, two of said arms 20 being alined adjacent one side of the tubular portion and the third rising and extending
- away from the opposite side of the tubular portion.
22. A windmill comprising a swivel mounted frame, a windwheel shaft mounted 25 in said frame, a windwheel on said shaft, and wind strain distributing means for steadyng said shaft in said frame embodyng a pair of cranks driven by said shaft, and a shaft for said cranks one of said 30 cranks being rotatively loosely mounted on said shaft for said cranks, said frame providing bearings for said shafts including a bearing for the crank shaft intermediate the cranks.
- 35 In testimony whereof I hereunto affix my signature in the presence of two witnesses.

HERBERT H. MACOMBER.
